UNITED STATES PATENT OFFICE

WILLIAM F. CHINIQUY AND WILLIAM O. WINCH, OF CHICAGO, ILLINOIS.

PROCESS AND MACHINE FOR SHAPING AND PRESSING HATS.

1,108,428.

Specification of Letters Patent.

Patented Aug. 25, 1914.

Application filed March 18, 1914. Serial No. 824,899.

To all whom it may concern:

Be it known that we, WILLIAM F. CHINIQUY and WILLIAM O. WINCH, citizens of the United States, residing at Chicago, in the county of Cook and State of Illinois, have invented certain new and useful Improvements in Processes and Machines for Shaping and Pressing Hats, of which the following is a specification.

Our invention relates to a machine or apparatus for pressing and forming hats constructed of straw and other woven braid or of felt and similar fibrous material that has previously been treated with sizing or other shape retaining substance.

In the manufacture of straw or similar hats it is usually the practice to stitch or sew the braid in a spiral manner so that one convolution thereof will overlap the preceding convolution until the proper quantity has been built up to form a "shape" of the desired proportions. After the braid has been stitched together, it is customary to treat or size the same with glue or similar fluid so that when the rough "shape" has been pressed over the form and dried it will retain its shape, for an indefinite length of time.

It is the object of our invention to construct an apparatus that is adapted to receive the sized hat "shape" and press the same together so that when the hat has been removed therefrom it will be in a finished condition.

Another object of our invention is to provide suitable means whereby hat forms of various shapes and dimensions may be accommodated in the same apparatus.

Still another object is to construct a machine to accomplish the above results in as simple a manner as possible and which is efficient as well as economical in its operation.

These and other objects we accomplish by the means and in the manner hereinafter fully described and as more particularly pointed out in the claims, reference being had to the accompanying drawings, which is a vertical transverse section taken centrally through our improved machine for pressing and forming hats.

In connection with the following description it is desired to here state that for convenience the machine has been described in connection with hats formed from braided straw and the like, and while we show and

describe specific elements for carrying out the objects of our invention, it, of course, is obvious that various changes, modifications and substitutions may be made thereto without departing from the spirit of our invention. All such changes and modifications we desire it understood are included within the scope of our invention as set forth in the appended claims, and we also desire it understood that hats made from felt, beaver or the like as well as straw-braid, may also be pressed and formed by our apparatus.

Referring to the drawing, 1, 1, represents suitable upright standards or posts that are preferably of a height sufficient to support the apparatus in a convenient horizontal position for the workman. Mounted upon and supported by the upper ends of these posts is a horizontally disposed frame 2 of substantially circular or ring shape. Removably placed upon this frame 2 is a suitable hollow or double bowl or similar vessel, 3, that is provided with a lateral shoulder 3^a adapted to rest on the circular frame. Said bowl preferably comprises a lower compartment 4 that dips a considerable distance below the horizontal plane of the circular frame and the side walls, 5, of which incline upwardly from the bottom and then outwardly and then vertically in substantially the manner shown in the drawing to form an ogee curve for the upper rim 6 thereof. From this upper rim the wall slopes downwardly at an angle of substantially forty-five degrees (45°) and then turns in a horizontal plane to form a substantially funnel shaped receptacle having a bottom 7 and inclined sides 8. This construction provides a closed compartment to which heat in the form of steam, hot air or the like, is adapted to be admitted through an inlet pipe 9 controlled by a valve 10, which heat, after circulating in said compartment, is discharged therefrom through exhaust pipe 11.

A suitable annulus or gasket 12 is adapted to be placed in the upper receptacle in such manner that the top thereof will be level with and in approximately the same horizontal plane as the upper edge or rim of said receptacle and said annulus has its outer face beveled or doweled as shown in order to make a substantially tight fit and conform to the shape of the adjacent surface of the receptacle. A portion of the inner vertical wall of said annulus is cut away as shown to

form a shoulder 12^a upon which a hat-form 13 of the dimensions and style it is desired to shape the hat is adapted to be seated. This hat form 13 is preferably made of 5 strong material and is provided with a plurality of radial passages or channels 14 that extend through said form and communicate with the interior of the upper receptacle. The annulus 12 and the hat form 13 are 10 adapted to fit into the open portion of the receptacle so tightly that the same will be substantially air-tight excepting at the passages 14 above mentioned, and when the latter are closed as will hereinafter be described, the air in said receptacle is exhausted therefrom by means of a suction pipe 15 tapped into the bottom of said receptacle and passing axially through the lower heat compartment to a suitable exhaust pump (not shown). In order to 20 tightly close the passages in the hat-form 13 we prefer to place the sized straw hat blank 16 in the hat-form and then cover the same, together with the exposed portions of the 25 form and the annulus with an elastic rubber sheet 17.

In operation the hat-blank having been placed in proper position and covered with the rubber sheet, the heat is admitted to compartment 4 and at the same time the suction pump is started. As the air exhausts from the upper receptacle and the vacuum therein becomes greater the elasticity of the rubber permits the sheet to be drawn down tightly 35 and firmly against the inside or upper surface of the hat form and blank which will cause considerable pressure to be exerted upon the latter and this being performed while the same is heated will press the braid 40 of which the hat is made into the desired shape as will be understood. At the same time the rubber sheet will cling or be drawn tightly against the various parts of the apparatus where there would be any liability 45 of destroying the vacuum which it is desired to maintain.

Having described our invention what we claim is:—

1. A machine for shaping and pressing 50 hats comprising a double-walled vessel, means for introducing heating fluid between

the walls of said vessel to produce a superheated condition within the same, a perforate hat form mounted on said vessel, and means for exhausting air from between said 55 hat form and said vessel during the superheated condition of the latter.

2. A machine for shaping and pressing hats comprising a double-walled vessel, means for causing the circulation of a heating fluid between the walls thereof, a perforate hat form mounted above the upper wall of said vessel and spaced therefrom, an impervious tissue adapted to cover said vessel and hat form, and means for exhausting air 60 from between said hat form and said vessel during the circulation of said heating fluid.

3. A machine for shaping and pressing hats comprising a double-walled vessel, means for introducing heating fluid between 70 the walls of said vessel to produce a superheated condition within the same, a gasket fitting said vessel, a perforate hat form seated on said gasket, and means for exhausting air from said vessel during the 75 superheated condition of the latter.

4. A machine for shaping and pressing hats comprising a double-walled vessel, means for causing the circulation of a heating fluid between the walls thereof, a gasket 80 fitting said vessel, a perforate hat form mounted on said gasket, an impervious tissue adapted to cover said vessel, hat form and gasket, and means for exhausting air from said vessel during the circulation of 85 said heating fluid.

5. A process for shaping and pressing hats comprising the placing of a hat blank upon a perforated form disposed upon a superheated vessel, the covering of said hat form 90 and vessel with an impervious tissue, and the exhausting of air from said vessel while said superheated condition is maintained therein.

In testimony whereof we affix our signatures in the presence of two witnesses.

WILLIAM F. CHINIQUY.
WILLIAM O. WINCH.
